(57) **CLAIM**

The ornamental design for a dock fixture for testing handheld electronic device, substantially as shown and described.

DESCRIPTION

FIG. 1 is a front perspective view of a dock fixture for testing handheld electronic device showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines in the Figures are for illustrative purposes only and form no part of the claimed design.

1 Claim, 4 Drawing Sheets*FIG. 1*

FIG. 2

FIG. 3

FIG. 4

FIG. 5

FIG. 6

FIG. 7
